(57) **CLAIM**

The ornamental design for an attachment for securing a therapy device, as shown and described.

DESCRIPTION

FIG. 1 is a top, front, and left side perspective view of an attachment for securing a therapy device.

FIG. 2 is a bottom, rear, and right side perspective view of the attachment for securing a therapy device of FIG. 1.

FIG. 3 is a top plan view of the attachment for securing a therapy device of FIG. 1.

FIG. 4 is a bottom plan view of the attachment for securing a therapy device of FIG. 1.

FIG. 5 is a left side view of the attachment for securing a therapy device of FIG. 1.

FIG. 6 is a right side view of the attachment for securing a therapy device of FIG. 1.

FIG. 7 is a front view of the attachment for securing a therapy device of FIG. 1; and,

FIG. 8 is a rear view of the attachment for securing a therapy device of FIG. 1.

The broken lines in the drawings are for illustrative purposes only and form no part of the claimed design.
